PENETRATIVE IMPLEMENT

Edward J. Ovington, Auburndale, Mass.

Application May 29, 1934, Serial No. 728,103

2 Claims. (Cl. 223—102)

This invention relates to improvements in penetrative implements.

More especially it relates to sharp pointed implements, such as needles and awls, for making small holes in material, either for the introduction of a thread, or the like, or for some other purpose; and it is especially applicable where the implement is to be withdrawn, and the hole which it has made is thereafter to be filled or 10 otherwise closed.

As the invention relates to that part of the implement which functions in the making of the hole, the invention is useful both where that is the whole function of the implement, as in the 15 case of an awl, and also where the implement serves some further function as the introducing of a thread, as in the case of a needle.

Thus the invention has utility in a considerable number of aspects. Fields of primary importance are for the sewing of leather and of 20 living tissue. As the sewing of leather is illustrative of the manner in which the invention functions when applied to other materials, and of its construction for attaining the results which 25 are to be described, the characteristics of the invention will be herein described with reference to needles for the sewing of leather, and also with some reference to surgery; but it will be understood that the utility and the advantages 30 are not limited to the materials named, or the particular uses described.

The implement of the invention has an improved construction which as applied to the sewing of leather is adapted to make the requisite 35 hole through the leather by an improved cutting and bending method of formation. In addition, the hole itself is what may be called an improved hole, that is, the walls surrounding the hole stand in a condition and in mutual relations 40 which have special advantages believed to be new; and the completed sewn article is an improvement over articles sewn with thread as heretofore known; so far as I am aware.

Objects of the invention are that the implement, as it penetrates, shall cut a tongue of the material and then bend or press that tongue away; meantime gradually and cleanly extending the cut, with the cutting in advance of the bending, and without tearing the tissue. The 50 initial cutting of the material is on a curved line, as on an arc of a circle; and the hole thus started is enlarged by the double operation of gradually extending the cut in arcuate form at each end of the initial arc, thus making a flap 55 of the material which is on the concave side of

the arcuate cut, and then displacing the tip of that flap by smooth pressure. If the material be leather, the displacing takes the form of a bending of the flap out of its original position in the plane of the material, and then the 5 surrounding walls of the ultimate hole are in part a surface cleanly cut by the needle, and are in part an indent surface which was initially an exterior surface of the material. If the material be living tissue the displacing takes the form 10 of a compressing and lateral flow of surrounding tissue. In both cases ragged edges and torn tissues are avoided, which is a matter of human consequence if use of the needle happen to be surgical, as well as one which in any case affects 15 the strength and durability of the sewing. In the case of the sewing of leather this is of particular importance. Leather is inherently resilient, and the little bent flap, upon being displaced from its normal place in the sheet of 20 leather, presses back against the thread which occupies the hole. If it happens that the flap has been put back into the hole, which can be done by the presser foot and the draft of thread in a sewing machine, the flap presses tightly 25 against the intruded thread and holds the sewing more firmly than if there were merely a punched round hole of the size of thread. In the case of patent leather the invention avoids 30 the striae of cracks and incipient rents which surround stitching holes punched by ordinary needles.

As applied in surgery, the U-shaped characteristic of the arcuate line of cut stops accidental trauma. When the arc is extended through so 35 many degrees of curvature that the end portions approach parallelism, any accidental pressing of the hand of the surgeon toward either side does not extend the cut sidewise and make the hole unnecessarily large. This shape of needle hole also makes the wound of such form as to have a best chance of healing quickly and of 40 leaving the least scar. The tissue on the concave side of the needle is under compression parallel to the surface in all directions from the 45 concave face of the needle. The tissue is by nature resilient, and this compression extends to that part of the tissue which is about to be cut. The presence of a state of compression there, as contrasted with the presence of a state 50 of tension and stretch, tends to prevent tearing of the tissue at the points which are about to be cut.

The cutting portion of the needle passes 55 through the material with relatively slight re-

sistance, because all of the rupturing necessary to be done is done by cutting; and this is done only gradually and with a drawing cut by the blades, as the penetration proceeds. Also, it is done with a thinner wedge of blade than with prior needles.

In the construction and maintenance of the needle, the cutting edges can be brought up to sharpness with but little or none of the hand operation which is known as the "finish pointing". Moreover, the invention makes the cutting part of the needle so that its sharp edges can easily be re-sharpened.

Other advantages result from or are found in the construction and mode of operation herein-after described. The particular embodiments of the invention herein described are illustrative, and the invention may be applied in other ways without departing from the spirit and scope of the invention. It is intended that the patent shall cover, by suitable expression in the appended claims, whatever features of patentable novelty exist in the invention disclosed.

In the drawing:

25 Figure 1, which may be considered to be a plan, shows a needle embodying the invention, having a shank of the straight round type, laid with its concave face upward, the edges of the concave face being the cutting edges of the needle;

30 Figure 2 is a side elevation of the same; Figures 3, 4, 5 and 6 are cross sections of the same at the places indicated, being end elevations, but in Figure 6 there is added a representation of a bit of sheet material as penetrated by the needle at this cross section thereof, showing the face of that material;

35 Figure 7 is a side elevation of the same needle in the act of penetrating two sheets of material;

Figure 8 is a plan of a fragment of the material 40 of Figure 7 from which the needle has been withdrawn and in which the flap has returned to its initial position, showing the effect of the needle upon the material;

Figure 9 is a section in side elevation 45 through two sheets of material and a hole therein made by the needle, showing a loop of thread therein;

Figure 10 is a similar section in side elevation showing two loops of thread in such a hole, looped 50 together, the material thus constituting a sewn article;

Figure 11 is a side elevation of another form of the needle, being a curved needle, embodying the invention;

55 Figures 12, 13 and 14 show some other forms of cross-section which either of the needles of the invention may have;

Figure 15 is a representation of a body of living tissue being penetrated by a needle of the invention, in which the stippling indicates compression effected by the needle which is seen in cross-section; and

60 Figure 16 represents in edge elevation a grinding wheel for sharpening the needle of the invention, this needle being seen in cross-section.

In the implement of the invention, whether it have an eye or be merely an awl, and whether it be straight or curved, the shank tapers to a point for penetrating the material; this tapering 70 portion of the implement has at least two cutting edges; and the surface connecting these edges is concave, and is herein referred to generically as being of U-form. The concavity is preferably of the general style of a crescent, as indicated in 75 Figures 3, 4, 5 and 12. At all stages of size of

the crescent, the curvature preferably reaches to a considerable extent of angular measure. The concavity and the crescent formation may vary somewhat, especially in different needles, illustrations of which are found in Figures 12, 13 and 14; but it will be noted that in each of these cases it has been preferred to extend the curvature to so large a fraction of a circle that a shape approaching a U is formed, and that consequently a pressure of the needle toward the right or left, 10 for example in Figures 3, 4, 5, 12 or 14, would not be favorable for cutting material on that side of the needle. This safeguards the material against the cutting of an unnecessarily large hole by side pressure of the operator's hand.

15 In the construction represented in the drawing, the needle of Figure 1 is represented with a shank 10 having an eye 12 and a tapering portion 14 leading to an extreme point portion 15. The eye is shown at the dull end, but it might be at the middle or near the point; or means other than an eye might be provided for drawing thread; or all devices of the sort might be omitted, as in the case of an awl. The tapering portion has cross sections, as seen in Figures 3, 4 and 5, whose shapes may be described in general terms as being crescent, although the two faces are not necessarily circular curves. The edges where those two curved sides intersect are sharp cutting edges marked *a*, *b*. The taper preferably is long, and these cutting edges depart so little from parallelism that the passing of the tapered part through material, as leather, or live tissue, presents the thin wedge blade to the material with such a slow enlargement of dimension between the two cutting edges of the blade that the cutting is done with a drawing of the blade edge along the material, to which there is very little resistance. When this implement is thrust endwise through a sheet of leather or other dead material, as represented at 20 in Figure 7, the material ultimately becomes cut on a curved line as represented at 22 in Figure 8; and the flap consisting of the tongue thus formed becomes bent out of the plane of the sheet 20 as the needle progresses, as seen in Figure 7, until finally, when the full body of the shank is passing through, having the cross section seen in Figure 6, the flap 24 is so far bent downward thereby that the hole is cut and spread open as there shown, ready to receive whatever thread may be drawn through by the eye 12, or be otherwise inserted.

55 Figure 9 represents a thread as thrust through the hole and left thereby a needle. This figure shows how the flap 24 of the material tends by resilience to press the thread, as the flap tends to return to its position illustrated in Figure 8. The thread is thus more tightly gripped than if there were a mere round hole made by the needle. And when that flap has been pulled back, as it may be by friction and thread tension upon withdrawal of the needle, to the position represented in Figure 10, the pressure of the flap upon the thread in the plane of the material is manifested.

70 A material such as the live tissue of man, or animals, is resiliently mobile in high degree. Around an incision into which needle and thread have been introduced it can undergo compression; and the tissue transmits pressure in all directions somewhat as a fluid does. Therefore the tissue at both sides of each cutting edge *a* and *b* in Figure 15 is in a state of compression from the gradual thickening of the intruded concave-con-

vex body of the implement represented in Figure 15; and by its native resiliency it can then tend strongly to return to its former position upon the withdrawal of the needle; and it will then remain 5 in compression owing to the presence of the thread which remains as an intruded body. In entering, the concavity of the one face diminishes the stretching or spreading effect which the implement is imposing on the tissue at the region 10 of the blade edge, as compared with a blade whose wedge-form is plane on one or both sides or is convex on both sides. Unlike a needle which merely makes a straight cut and at the same time bulges it, or one which radially enlarges a small 15 hole made by the very point of the needle, both of which tear the tissue more or less in the making of the hole, this needle makes the hole by first curving a flap and then pressing aside the flap. Thus the walls surrounding the hole are cleanly 20 cut and hence relatively smooth, regular and firm, and automatically tend to close together, both in the case of leather and of living tissue. Therefore the thread is more firmly held than it is in ordinary sewing; the article thus sewn has its 25 material in a state of resilient compression against intruded thread; and the frictional holding is secure and very strong, the part which is compressed within the thickness of the material continuing to hold the thread.

30 When the needle's cut through the material is clean, as represented in Figure 8, and the ends of the cut approach a parallelism of direction, as there indicated, the walls of each hole are in condition to resist strongly a seam tension without 35 tendency of the holes to become enlarged by extension of incipient radial rents, such as might have been already started if a needle of some other type had been used.

In the needles of the invention, it is desirable 40 that the curves of the crescent as seen in cross section should bear approximately the same relation to each other at all sections of the taper, as is seen by comparing Figures 3, 4 and 5.

In manufacturing the needle of the invention 45 the concave tapering portion can be made by a stamping process which deforms a round pointed blank of the material into the desired concave crescent shape. In such a blank there will al-

ready have been an accurate round pointing of the round needle wire according to the contour of a predetermined curve. This contour is preferably convex from point to shank, but the degree or curve of convexity depends upon the rate 5 at which the various dimensions of the crescent cross-section are desired to increase. Then, when the blank is by a press operation struck into a crescent cross-section, the edges will come up into shape in fairly sharp cutting condition with little 10 or no extra metal appearing as a flash around the actual edge. Even when finish pointing is necessary, it can be done much more easily with this type of needle than with flat sided needles of former type. When the needle shape has been 15 made by stamping, the edges *a* and *b* can be made sharp by the simple procedure of holding the needle on the surface of a V-shaped recess in a grinding wheel, as indicated in Figure 16.

The terms "concave" and "convex" are herein 20 used as being comprehensive of surface forms which are variously re-entrant or variously salient respectively, several of which are seen in the drawing.

I claim as my invention:

1. A penetrative implement of the class described, having a portion which tapers to a sharp point and in the taper has sharp cutting edges precisely two in number; said tapering portion having a forward side and a rear side, of which the forward side has a channel contour throughout said taper, and the rear side has a salient contour throughout said taper; the two said contours merging into the two said cutting edges, 30 which extend along opposite borders of said channel to the extremity of the said point, each cutting edge being the edge of a sloping surface of the channel contour.

2. A penetrative implement as in claim 1, further characterized in that the tapering portion is of approximately crescent shape in cross-section throughout the taper to the extremity of the point, with the two cutting edges extending along the two horns of the crescent, the grinding of each edge, for sharpness, being on the said salient side thereof.

EDWARD J. OVINGTON.
